[57] CLAIM

The ornamental design for a door handle, substantially as shown and described.

DESCRIPTION

FIG. 1 is a perspective view of a door handle showing my new design;

FIG. 2 is a top plan view thereof;

FIG. 3 is a side elevational view thereof;

FIG. 4 is a bottom plan view thereof;

FIG. 5 is a left end elevational view thereof; and

FIG. 6 is a right end elevational view thereof.

The opposite side elevational view is a mirror image of FIG. 3.

FIG. 2

FIG. 5

FIG. 3

FIG. 6

FIG. 1
